US0D1046028S

(12) **United States Design Patent** (10) **Patent No.:** **US D1,046,028 S**
(45) **Date of Patent:** **** Oct. 8, 2024**

(54) **SMART FITNESS EQUIPMENT**

(71) Applicant: **Shanghai Daishi Electronic Technology Co., Ltd.**, Shanghai (CN)

(72) Inventor: **Ning Xie**, Jiangsu (CN)

(**) Term: **15 Years**

(21) Appl. No.: **29/832,711**

(22) Filed: **Mar. 29, 2022**

(51) **LOC (14) Cl. 21-02**

(52) **U.S. Cl.**

USPC **D21/671**

(58) **Field of Classification Search**

USPC D21/662, 670, 671, 685, 686, 817, 688

CPC . A47C 27/146; A63B 22/0076; A63B 21/227;

A47G 9/10

(57) **CLAIM**

The ornamental design for a smart fitness equipment, as shown and described.

DESCRIPTION

FIG. 1 is a perspective view of the smart fitness equipment showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings are included for the purpose of illustrating portions of the smart fitness equipment that form no part of the claimed design.

1 Claim, 8 Drawing Sheets
